WINDING MACHINE

Elmer R. Duncklee, Mystic, Conn., assignor to
 The Atwood Machine Company, Stonington,
 Conn., a corporation of New Jersey

Application September 10, 1935, Serial No. 39,912

2 Claims. (Cl. 242—18)

This invention relates to textile winding machines and particularly to a yarn or thread winding machine adapted for conversion from a single deck to a double deck winding machine with minimum alterations and additions.

An object of the present invention is to provide spool supporting brackets for a winding machine so that they may be used for mounting spools for a single deck winding machine and, by the addition of a short auxiliary arm pivotally supported on each of the brackets, adapt the machine for a second deck of spools.

Another object of the present invention is to provide a spool supporting bracket for a single deck winding machine having a projection thereon which may be provided with spool supporting bearings carried on a short arm pivotally adjustable upon the projection or a fixed part of the bracket so that these additional bearings may be used for supporting spools of a second deck or series of spools in engagement with the friction driving wheels used for the spools of the first deck.

And finally it is an object of the present invention to provide a winding machine with brackets having fixed bearings therein, the brackets being adapted to have supplementary bearings mounted thereon for independent adjustment relative to the fixed bearings.

With the above and other objects in view, my invention includes the features of construction and operation set forth in the following specification and illustrated in the accompanying drawing.

In the accompanying drawing annexed hereto and forming a part of this specification, I have shown my invention embodied in a standard form of winding machine, but it will be understood that the invention can be otherwise embodied and that the drawing is not to be construed as defining or limiting the scope of the invention, the claims appended to this specification being relied upon for that purpose.

In the drawing:

Fig. 1 is a plan view of a portion of a winding machine having the present invention applied thereto; and

Fig. 2 is a side elevation partly in section of the parts shown in Fig. 1.

In the above mentioned drawing, I have shown but one embodiment of the invention which is now deemed preferable, but it is to be understood that changes and modifications may be made within the scope of the appended claims

without departing from the spirit of the invention.

Briefly and in its broadest aspect, my invention may include the following principal parts; first, an arm or bracket supported on and outstanding from a frame member of the machine; second, bearings on said bracket for adjacent ends of adjacent spools being wound on said machine; third, traverse bar supporting means on some of said brackets; fourth, a projection vertically disposed on said bracket; fifth, an arm pivotally mounted on and adjustable in a vertical plane relative to said projection and having bearings thereon for adjacent ends of adjacent spools of a second series; and sixth, a traverse bar supporting member clamped to said bracket and retaining said bracket in position on said machine.

Referring more in particular to the figures of the drawing, I provide an arm or bracket 10 outstanding from and secured to the winding machine side bars 11 and 12. One of the particular brackets illustrated is provided with an extension in which is rotatably mounted a roll 13 on which a traverse bar 14 may reciprocate while being supported within a recess formed in the extension. It will be understood that but few of the brackets 10 with rolls 13 will be required in any one machine. Those without the extensions are similar to that shown in the upper portion of Fig. 1 and each type has provision for supporting spools of either one or two series.

On each type of bracket 10 there are provided bushings 15 forming bearings for the ends of adjacent spools 16. As is usual in bearings of this type, the bearing for one end of a spool is in the form of a recess and the bearing for the opposite end of an adjacent spool is an inclined flat surface. Preferably the bushings forming the bearings are of wood. In practice each spool 16 is mounted on a spindle 17, the ends of which extend to and engage the bearings in bushings 15. A small pulley 18 on the spindle 17 adjacent the end of the spindle bearing having the inclined flat surface rests upon and is driven by a friction wheel 19 of the usual type mounted below each spool 16.

The above described parts are standard and those usually found in winding machines of the type employing the present invention. Further description therefore will be unnecessary.

On the brackets 10 are provided vertically extending projections 20 disposed between the bushings 15 and the end attached to the frame rods 11 and 12. On the projection 20 for each

of the brackets 10 is a pivotal bearing or connection for a short auxiliary arm 21. The arms 21 for each bracket 10 are similar to each other and each is provided with a bushing 22 similar 5 in every way to the bushings 15 provided directly in the bracket 10. A second series or deck of spools 23 may therefore be supported upon the brackets 10 by means of these arms 21, these spools 23 being rotated by spindles 24 having 10 pulleys 25 engaging the friction wheel 19.

In order to pivotally adjust the arm 21 upon the projection 20, there is provided an arcuate slot 26 in the projection. A screw 27 having a nut on its outer end extends through an opening in the arm 21 and through the arcuate slot 26 so that the arm 21 may be clamped in any adjusted or predetermined position.

To provide a traverse bar 28 for the second deck of spools 23, there is provided a support 29 having a roller 30 therein and permitting reciprocation of the bar 28 in the same manner as bar 14 in the extension of bracket 10. For convenience the support 29 is made a part of the clamping member 31 for the bracket.

The brackets 10 supplied with single deck winding machines in which spools 16 only are employed would have the projection 20 with the necessary opening and slot 26, but there would be no arms 21 pivotally mounted thereon. The 25 clamping members 31 would not have the extensions forming the supports 29. So equipped the winding machine would be substantially a standard single deck winder. To convert a winding machine as above described into a double deck winder, it would be necessary only to add the arms 21 upon the brackets 10 which could be done without disassembling the machine, and to substitute the clamping members 31 shown in the figures and the second traverse bar 28 for 30 the parts without extensions 29. Thus changed over the machine would be doubled in capacity with the slight additions necessary without the necessity of rebuilding the machine. The 35 adjustments necessary to get proper driving contact for the pulleys 18 and 25 on the spindles 17 and 24 for the spools 16 and 23 with friction 40 45

wheel 19 may be made independently for each deck.

With the bearings 15 properly adjusted in any usual manner when the machine is originally set up as a single deck winding machine it is only 5 necessary to adjust the pivotal position of the arms 21, when converting the machine to a double deck winder, to give the proper contact of the pulleys 25 with the friction wheel 19. This adjustment does not affect the previous 10 adjustment of the brackets or of the fixed bearings 15 therein.

I claim:—

1. In a winding machine in combination, supporting brackets mounted on said machine having fixed bearings adjacent their outer ends for a series of spools being wound, driving wheels rotatably mounted below said brackets for rotating spools thereon, arms pivotally mounted intermediate the ends of said brackets having bearings therein at their free ends for supporting spools of a second series of spools being wound, said second series of spools being driven from said driving wheels for said first series of spools, means to secure said brackets in fixed position 25 relative to said wheels, and means to secure said pivotally mounted arms on said brackets in adjusted positions relative to said wheels.

2. In a winding machine in combination, supporting brackets mounted on said machine having fixed bearings adjacent their outer ends for a series of spools being wound, driving wheels rotatably mounted below said brackets for rotating spools thereon, projections formed intermediate said brackets, arms pivotally mounted 35 on said projections having bearings therein at their free ends for supporting spools of a second series of spools being wound, said second series of spools being driven from said driving wheels for said first series of spools, means to secure 40 said brackets in fixed position relative to said wheels, and means on said projections to secure said pivotally mounted arms in adjusted positions relative to said wheels.

ELMER R. DUNCKLEE.
